UNITED STATES PATENT OFFICE.

LOUIS N. D. WILLIAMS, OF OGONTZ, PENNSYLVANIA.

RIB-KNITTING MACHINE.

1,163,295.

Specification of Letters Patent.

Patented Dec. 7, 1915.

Application filed June 19, 1913. Serial No. 774,592.

To all whom it may concern:

Be it known that I, LOUIS N. D. WILLIAMS, a citizen of the United States, residing in Ogontz, Pennsylvania, have invented certain 5 Improvements in Rib-Knitting Machines, of which the following is a specification.

My invention relates to that type of knitting machines in which are employed two needle carriers at an angle to one another, 10 such, for instance, as the vertical needle cylinder and horizontal needle dial of an ordinary rib knitting machine. In such machines, the knitted web, in its passage from the needles to the take-up mechanism, usually 15 passes between dogs which retain the cylinder and dial in their proper circumferential relation and, with dogs of the ordinary construction, much difficulty is experienced in inserting the web between the 20 dogs in the first instance, while the jabbing of the fabric on the needles preparatory to a resumption of knitting, in the case of a "press off," causes an increase of bulk in the web which, when it passes between fixedly 25 mounted dogs, has the effect of throwing the needle carriers out of proper registry and prevents the normal operation of the machine at that time. In carrying out my invention, therefore, I so mount the dogs that 30 one or either of them can be moved away from the other, thereby providing, between the dogs, a space of such size that the knitted web can be readily passed between the dogs, the latter being then permitted to approach 35 one another in order to assume their normal or operative relation.

In the accompanying drawings—Figure 1 is a view, partly in plan or top view and partly in horizontal section, of one form of 40 dogging device constructed in accordance with my invention; Fig. 2 is a transverse section of the same on the line *a—a*, Fig. 1; Fig. 3 is a detached view of the cylinder dog; Fig. 4 is a view similar to part of Fig. 45 2 but illustrating another type of locking device for the cylinder dog; Fig. 5 is a section on the line *b—b*, Fig. 4; Fig. 6 is a face view of another portion of the device; Fig. 7 is a view similar to Fig. 1 but illustrating 50 a cylinder dog different from that shown in the latter figure; Fig. 8 is a view, partly in elevation and partly in transverse section, on the line *c—c*, Fig. 7; Fig. 9 is a transverse section illustrating a modified 55 form of adjusting device for the dog carried by the dial of the machine; Fig. 10 is a view,

partly in elevation and partly in section, on the line *d—d*, Fig. 9; Fig. 11 is a section on the line *e—e*, Fig. 9, showing in elevation part of one of the elements of said adjusting device; Fig. 12 is a view similar to Fig. 2, but illustrating a modified form of pivotal mounting for the cylinder dog; Fig. 13 is a transverse section on the line *f—f*, Fig. 12, and Fig. 14 is a view illustrating 65 a further modification.

In the various figures of the drawing, 1 represents part of the needle cylinder of a knitting machine and 2 part of the dial of the same, these members of the machine being either fixedly or rotatably mounted in their supporting structures, depending upon whether the cam carriers of the machine are rotatable or fixed. In order to preserve these members of the machine in proper circumferential relation to one another they are provided with dogs of which the cylinder dog is represented at 3 in Figs. 1 and 2 and the dial dog at 4 in said figures. The web of fabric produced upon the machine 70 has to pass between these dogs in its passage from the needles to the take-up mechanism and much difficulty is often experienced in introducing the forward portion of the web between the dogs, the latter being adjusted 75 so that their adjoining surfaces are nearly in contact with one another, only sufficient space being left between them to compensate for the thickness of the web which is being produced upon the machine. In order to 80 overcome this objection I provide for an abnormal separation of the adjoining faces of the dogs at the time when the web is being introduced, or when a portion of web of 85 abnormal thickness has to pass between them and for a subsequent adjustment of said dogs to their normal working position. But one of the dogs may be adjustably mounted but I prefer to so mount both of 90 them and I have provided various means in connection with such adjustable mountings for locking the dogs in their proper normal 95 relation to one another after the knitted fabric has been introduced between them.

In the construction shown in Figs. 1 and 2 the cylinder dog 3 has a pivot stem 5 with enlarged head 6 at its lower end, said pivot stem and its head being pivotally mounted in a bearing in a boss 7 secured to the inner face of the cylinder 1, so that the dog 3 can 100 swing rearwardly on its pivot stem 5 in the absence of any means for preventing it from 105 110

doing so. In the boss 7, however, is rotatably mounted a vertical locking bolt 8 having an eccentric head 9 projecting above the boss and at the rear of the dog 3, so that, when the full diameter of said head is presented 5 for contact with the back of the dog, the latter will be locked against any swinging movement on its pivot but when the reduced portion of the head is thus presented 10 the dog will be allowed to swing rearwardly to the extent of such reduction. At the lower end of the locking bolt 8 is an arm 10 provided with a spring-actuated bolt 11 which is adapted to engage with one or other of a 15 pair of notches formed in the under face of the boss 7 so as to retain the locking bolt in either of its two positions of adjustment. The dial dog 4, by preference, consists of a roller which is rotatably mounted by means 20 of a ball bearing or other anti-frictional device upon one end of a lever 12, the latter being pivoted, by means of a depending stud 13, to the underside of the dial and having, adjacent to its other end, an opening for the 25 passage of a screw stem 14 whose threaded portion is adapted to a threaded opening in a stud 15, also depending from the underside of the dial, a lock nut, set screw, or other available means being employed for 30 preventing said screw stem 14 from turning after it has been properly adjusted. Loosely mounted on the screw stem 14 are a pair of washers 16 one bearing against the stud 15 and the other against the lever 12, 35 and between these washers is interposed a coiled spring 17 whose tendency is to move the lever 12 in the direction of the arrow α , Fig. 1, and thus separate the dog 4 from the dog 3. At one end of the screw stem 14, 40 however, is a head 18 and between the latter and the face of the lever 12 is interposed a washer 19, which has a cam face 20 coöperating with a similar cam configuration on the face of the lever. When, therefore, the 45 washer 19 is adjusted so that the high portions of its face are in register with the low portions of the cam face on the lever the latter will move under the influence of the spring 17 so as to separate the dog 4 from the cylinder dog 3 to an extent determined 50 by the configuration of the cam faces of the lever and washer, but when the washer 19 is turned so as to cause the high portions of its cam to register with the high portions 55 of the lever cam face, said lever will be adjusted so as to bring its dog 4 into normal operative relation with the dog 3 and will lock it in said position.

Figs. 4, 5 and 6 illustrate a modified construction of locking bolt for the cylinder dog 3. In this modification the locking bolt 8^a is mounted so as to slide vertically in the boss 7 and when said bolt is fully raised it contacts with the rear face of the dog and locks the latter in its normal position. The

upper end of the bolt, however, is notched, as shown at 21 in Fig. 6, and when the bolt has been lowered so as to bring its notched upper end into register with the dog 3 the latter can swing back into the notch and thus be separated to that extent from the dog 4. In order to provide for the raising and lowering of the bolt 8^a the latter is forked at its lower end and this forked portion is provided with a transverse pin 22 75 which also passes through a cam slot 23 in a disk 24 contained in a forked extension of the boss 7 and mounted so as to turn upon a pin 25 crossing said forked extension, as shown in Fig. 5, the disk 24 having a suitable handle 24^a whereby it can be easily manipulated.

In the modified structure shown in Figs. 7 and 8 the dog 3 has a pivot stem 5^a extending through the boss 7 from top to bottom 85 of the same and having at its lower end an arm 10 with spring-pressed locking bolt 11, similar to the corresponding parts employed in connection with the locking bolt 8 in the structure shown in Fig. 2. In this case the 90 dog 3 can be swung into either normal or separated relation to the dog 4 by manipulating said dog 3 through the medium of its pivot stem 5^a.

In the modification shown in Figs. 9, 10 95 and 11 the cylinder 1 has a fixed dog 3^a projecting from the inner face of the same and the lever 12, carrying the dial dog 4, has pivotally mounted upon it a supplementary lever 26, recessed so as to span the 100 screw stem 14, said recessed portion of the lever presenting cam faces 27 which when interposed between the face of the lever 12 and the inner face of the head 18 on the screw stem 14, as shown in Fig. 10, will 105 force the inner arm of the lever 12 rearwardly and bring its dog 4 into proper operative relation with the fixed dog 3 on the cylinder; and will lock it in such position. When, however, the outer end of the lever 110 26 is moved so as to withdraw its cam face from between the lever 12 and the head 18 said inner arm of the lever 12 will move forwardly so as to separate its dog 4 from the adjacent face of the cylinder dog 3^a. In 115 order to provide for the simultaneous locking or release of a series of dog-carrying levers 12, when the dial is provided therewith, I provide, on the underside of the dial, a ring 28 provided with a series of depending cams 29 one for each of the levers 12, these cams being adapted to act upon rollers 30 rotatably mounted upon the levers 26. The ring 28 is provided with stud bolts 31 125 projecting upwardly therefrom through suitable segmental slots 32 in the dial 2 and provided at their upper ends with nuts 33, so that when occasion requires the ring 28 may be moved circumferentially in respect to the dial so as to cause its cams 29 to act 130

simultaneously upon the rollers 30 of all of the levers 26, or so as to free said rollers from the influence of said cams, provision being thereby afforded for adjusting all of 5 the dogs 4 simultaneously in respect to the cylinder dogs 3^a. When the ring 28 is adjusted so as to free all of the rollers 30 from the influence of the cams 29 the levers 26 may be manipulated independently so as to 10 adjust either of the dogs 4 independently of the others. By rotating the ring 28 in respect to a stationary dial, or by holding said ring stationary when the dial rotates, each of the dial dogs may be separated from its 15 coöperating cylinder dog, on each rotation of the machine, if desired, and provision thus afforded for the tension mechanism to act upon those portions of the web which at other times are clamped between the dogs. 20 The cylinder dog, or each of such dogs when a series are employed, may be mounted upon a horizontal axis if desired instead of upon a vertical axis as hereinbefore shown and described, and in Figs. 12 and 13 I have 25 shown one method of thus mounting the cylinder dog, the latter having near the top an outwardly projecting pivot stud 35 free to turn in a suitable bearing in the cylinder, and having a projecting arm 36 which can 30 play in a recess in said cylinder, as shown in Fig. 13, said arm 36 being acted upon by a vertical rod 37 contained in an opening in the cylinder and acted upon at its lower end by a cam lever 38 so that it can be projected, 35 as shown in Fig. 12, in order to raise the arm 36 and hold the dog 3 in operative position, or can be lowered so as to release said arm 36 and permit the lower portion of the dog 3 to swing away from the dial dog. 40 When there are a series of similar dogs and a corresponding series of rods 37 the cams 38 may be mounted upon a ring so as to operate all of said rods 37 simultaneously, if desired. 45 In Fig. 13 I have illustrated a cylinder dog having a pivot stud 35^a at its lower end, the upper portion of the dog in this case being moved from and toward the dial dog. The movement of the dog may be effected by 50 devices similar to those shown in connection with the dog illustrated in Figs. 12 and 13.

I claim:

1. The combination, in a knitting machine, of two angularly disposed needle carriers, dogs for determining the proper relation of one of said needle carriers to the other, said dogs being so disposed that the knitted web passes between them, means for adjusting one of said dogs from and to 55 ward the other, means supplemental to said 60 adjusting means for locking the dogs in

normal position, and means for releasing said locking device so as to permit abnormal separation of the dogs.

2. The combination, in a knitting machine, of two angularly disposed needle carriers, dogs for determining the proper relation of one of said needle carriers to the other, said dogs being so disposed that the knitted web passes between them, a bolt operating in conjunction with one of said dogs and having a cam head, which, when in one position, locks the dog in normal operative relation to the other, and, when in the other position, permits abnormal separation of the 75 dogs, and means for operating said bolt so as to bring either portion of its cam head into operative relation with the dog.

3. The combination, in a knitting machine, of two angularly disposed needle carriers, dogs for determining the proper relation of one of said needle carriers to the other, said dogs being so disposed that the knitted web passes between them, a lever carrying one of said dogs, a spring acting 85 upon said lever and serving to retain its dog in one position in respect to the coöperating dog, and a cam device for acting upon said lever so as to carry its dog into another relation with the coöperating dog.

4. The combination, in a knitting machine, of two angularly disposed needle carriers, dogs for determining the proper relation of one of said needle carriers to the other, said dogs being so disposed that the 95 knitted web passes between them, a lever carrying one of said dogs, a screw stem passing through said lever and adapted to a stud on the needle carrier, a spring acting on the lever, a head on said screw stem, and a cam washer, interposed between said bolt and the lever, and serving, by its adjustment, to change the position of the latter.

5. The combination, in a knitting machine, of two angularly disposed needle carriers, dogs for determining the proper relation of one of said needle carriers to the other, said dogs being so disposed that the knitted web passes between them, devices for moving a dog of one carrier toward or 100 from a dog of the other carrier, means for effecting independent operation of each of a series of such devices, and means for effecting simultaneous operation of such series.

In testimony whereof, I have signed my name to this specification, in the presence of two subscribing witnesses.

LOUIS N. D. WILLIAMS.
